FIG. 16

FIG. 1 is a front elevation of an alternating to direct current converter showing our new design incorporated in a seven-module converter with a control unit;

FIG. 2 is a rear elevation of the embodiment of FIG. 1;

FIG. 3 is a side elevation as viewed from the right of FIG. 1;

FIG. 4 is a side elevation as viewed from the left of FIG. 1;

FIG. 5 is a top plan view of the converter of FIG. 1;

FIG. 6 is a front elevational view of an alternating to direct current converter showing a second embodiment of our new design incorporated in a fourteen-module converter with a control unit and high voltage conductors;

FIG. 7 is a rear elevation of the converter of FIG. 6;

FIG. 8 is a side elevation as viewed from the right of FIG. 6;

FIG. 9 is a side elevation as viewed from the left of FIG. 6;

FIG. 10 is a top plan view of the converter of FIG. 6;

FIG. 11 is a front elevational view of an alternating to direct current converter showing a third embodiment of our new design incorporated in a fourteen-module converter with a control unit and low voltage bus bars;

FIG. 12 is a rear elevation of the converter of FIG. 11;

FIG. 13 is a top plan view of the converter of FIG. 11;

FIG. 14 is a side elevation as viewed from the left of FIG. 11;

FIG. 15 is a side elevation viewed from the right of FIG. 11; and

FIG. 16 is an enlarged fragmentary sectional view taken on line 16—16 of FIG. 1 to bring out the grill ornamentation.

This is a division of design application Ser. No. 18,274, filed July 18, 1969 and now Pat. D. 222,146.

We claim:

The ornamental design for an alternating to direct current converter, substantially as shown and described.
